CLAIM

The ornamental design for a light fixture, as shown and described.

DESCRIPTION

FIG. 1 is a bottom perspective view of a first embodiment of a light fixture;

FIG. 2 is a bottom plan view thereof;

FIG. 3 is a top plan view thereof;

FIG. 4 is a right side elevation view thereof;

FIG. 5 is a left side elevation view thereof;

FIG. 6 is a front elevation view thereof;

FIG. 7 is a rear elevation view thereof;

FIG. 8 is a cross-sectional view of the light fixture taken along line 8-8 of FIG. 2;

FIG. 9 is an enlarged isolated view of a reflector of the light fixture of FIG. 8;

FIG. 10 is a bottom perspective view of a second embodiment of a light fixture;

FIG. 11 is a bottom plan view thereof;

FIG. 12 is a top plan view thereof;

FIG. 13 is a right side elevation view thereof;

FIG. 14 is a left side elevation view thereof;

FIG. 15 is a front elevation view thereof;

FIG. 16 is a rear elevation view thereof;

FIG. 17 is a cross-sectional view of the light fixture taken along line 17-17 of FIG. 11; and,

FIG. 18 is an enlarged isolated view of a reflector of the light fixture of FIG. 17.

Portions or features of the light fixture not shown in the drawings form no part of the claimed design. The broken lines in the drawings that illustrate portions of the light fixture form no part of the claimed design.
